CLAIM

The ornamental design for a window box mounting bracket, as shown and described.

DESCRIPTION

FIG. 1 is a perspective view of the window box mounting bracket showing my new design.

FIG. 2 is a front view of the device shown in FIG. 1.

FIG. 3 is a rear view of the device shown in FIG. 1.

FIG. 4 is a top view of the device shown in FIG. 1.

FIG. 5 is a bottom view of the device shown in FIG. 1; and, FIG. 6 is a one side view of the device shown in FIG. 1, the opposed side view being a mirror image thereof.
